UNITED STATES PATENT OFFICE.

FERDINAND PRELLER, OF HAMBURG, GERMANY.

MANUFACTURE OF WIRE SCREENS.

SPECIFICATION forming part of Letters Patent No. 243,790, dated July 5, 1881.

Application filed March 14, 1881. (No model.)

To all whom it may concern:

Be it known that I, FERDINAND PRELLER, a resident of the city of Hamburg, in the German Empire, have invented Improvements in the Manufacture of Wire Screens, of which the following is a specification.

In the wire screens for malt-kilns and other purposes heretofore in use the connection of the intersecting wires is made by means of thinner binding-off wires, which are placed diagonally across the points of intersection of the wires. This has the disadvantage that the ends of the thin connecting wires project and act like barbs, so as to injure the feet of those walking over the screens or coming otherwise in contact therewith. The binding-wires have also the further disadvantage that they soon wear out, disconnect the main wires of the screens, and render thereby the whole screen loose and shaky.

The object of this invention is to avoid these defects and connect the intersecting wires of wire-screens in such a manner that the diagonal binding-off wires are entirely dispensed with, and a screen is obtained which is at one side entirely flat and smooth without any projections, so as to be specially adapted for malt-kilns, ore-roasting kilns, middlings-purifiers, and grain-separators, as well as for plain cylindrical or conical screens.

The invention consists of a screen the longitudinal wires of which are made straight, while the transverse wires are provided with indentations below points of intersection with the longitudinal wires, and retained by side wires, which secure the reliable interlocking of the wires and the stiffening of the screen.

In the accompanying drawings, Figures 1 and 2 represent, respectively, a bottom and an end view of a wire screen made according to my improved method. Fig. 3 is a sectional side elevation of a set of rolls for imparting the proper indentations to the transverse wires of the screen. Fig. 4 is a top view of the rolls; Fig. 5, a detail vertical transverse section of one of the rolls. Figs. 6 and 7 are vertical longitudinal sections; Fig. 8, an end view, and Fig. 9 a top view, of my improved wire screen modified in such a manner as to be adapted for malt and other kilns; and Figs. 10 and 11 are, respectively, a sectional front eleva-

tion and a vertical transverse section of the tongs, by which the indentations of the cross-wires are closed, so as to be adapted for the wire screens for malt-kilns shown in Figs. 6 to 9. Fig. 12 is an enlarged view of Fig. 7. Fig. 13 is an enlarged view of Fig. 1.

Similar letters of reference indicate corresponding parts.

In Figs. 1 and 2 of the drawings is represented a wire screen of simple construction, made according to my method. The longitudinal wires *a* are straight throughout, and are firmly held at equal distances from each other by the transverse wires *b c d*. The middle wire, *c*, is provided at the points where it passes below the longitudinal wires *a* with semicircular bends or indentations by which the wires *a* are retained in position. The wires *b* and *d* are preferably provided with indentations at the points where they pass over the wires *a*, the indentations serving to bear on the opposite sides of the wires *a*, so as to secure them, in connection with the wires *c*, firmly and reliably in position. The wires *b* and *d* may, however, be straight, while the wire *c* requires in all cases the bends or indentations for the longitudinal wires *a*. The transverse wires *b c d* are either soldered together or connected by thin binding-wire wound around the same, as desired. This wire screen is entirely flat on one side, as shown clearly in Fig. 2, while on the other side the indentations of the wires *c* project somewhat to the under side, the thin binding-wire around the wires *b c d* projecting so little as to exert no injurious influence.

The indentations of the wires *c* are formed by the machine represented in Figs. 3 and 4 of the drawings, which consists, essentially, of two rolls, *A* and *B*, that are supported in side standards, *D*, the rolls being revolved by intermeshing gear-wheels of equal size at the ends of the roll-shafts and operated by hand or power, so that the uniform rotation of the rolls is produced. The rolls are provided with transverse channels *g*, into which accurately-fitting filling-pieces *f* are inserted, which are secured to the ends of the rolls by means of inwardly-bent ears *f'* and transverse fastening-bolts *f''*. The bolts *f''* pass through the rolls and are provided with a head at one end and at the opposite end with a fastening-nut. The

filling-pieces *f* are either of flat shape, so as to be flush with the circumference of the rolls, or of concave or convex shape. When the upper roll is arranged with convex filling-pieces, the lower roll must be arranged at the same distances with corresponding concave filling-pieces, while the channels intermediately between the convex and concave filling-pieces are filled up with flat filling-pieces *f*. In this manner one roll is provided with projections, while the other roll is provided with grooves, registering therewith, by the joint action of which the wires are fed through between the rolls and bent or indented at the same time, as shown in Fig. 3. The filling-pieces *f* are interchangeable in the transverse channels of the rolls, so as to admit the forming of wires having bends of different sizes or at different distances from each other, as desired. If a certain uniform size of indented wires has to be turned out it is preferable to make one roll with raised portions and the other roll with corresponding grooves, in place of the rolls with interchangeable filling-pieces. The rolls A and B are preferably of such width that at the same time a number of wires may be passed through between the rolls and be indented at proper intervals.

For a number of purposes, such as floors of malt-kilns and the like, the longitudinal wires are provided with indentations, which, however, are not made semicircular, as in the transverse wires heretofore described, but preferably nearly closed, so as to form an eye or loop, as shown in Figs. 6, 7, and 8. This is quickly accomplished by a set of tongs shown in Figs. 10 and 11, which consists of two fulcrumed jaws, *g*, the lower ends of which are connected by a screw-nut, *g'*, having a handle, *g²*, said screw-nut engaging two screw-bolts, one having a right-hand, the other a left-hand, thread, which bolts are pivoted to the lower ends of the fulcrumed jaws *g*. By turning the screw-nut *g'* in one direction the lower parts of the jaws approach each other, while the upper parts of the jaws are closed.

For exposing the wires to the action of the tongs the indented portions are placed on a former, *h*, and retained by a horizontal bracket-plate, *h'*, above and by lower seat or rest, *h²*, below the same, so as not to shift or otherwise change their position when the indentations are closed up, as shown in Fig. 10. The jaws of the tongs are made wide enough to admit the bending of a number of wires at the same time. Through the so-looped wires *a'* are passed strong transverse wires *b'*, while thinner transverse wires *c'* are placed into the bends at the upper parts of the loops close to the under side of the wires *a'*, as shown in Figs. 6 and 7. The distance between the longitudinal wires *a'* is regulated by short intermediate pieces, *i*, which are interposed between the wires *c'*. The outermost ends of the transverse wires *c'* are bent into the form of an eye, as shown in Fig. 8,

or are riveted to a flat piece of iron or sheet metal, so as to be retained securely at the edges of a panel of the screen.

According to the thickness of the intermediate pieces, *i*, the spaces between the longitudinal wires of the screens can be arranged with more or less width, while for very close screens it is preferable to use in place of the intermediate wire pieces, *i*, thin perforated sheet-metal strips.

The transverse wires *b'* and *c'* impart to the screen or kiln-floor great strength, so that they require to be supported at less points, and offer a greater surface for the passage of the hot gases in drying the malt.

As readily seen in Figs. 6 to 9 of the drawings, these screens or kiln-floors are entirely flat on the upper side, and constructed in such a manner that they do not give out until the longitudinal wires *a'* are entirely worn out at 85 their points of connection with the transverse stiffening and supporting wires.

Having thus described my invention, I claim as new and desire to secure by Letters Patent—

1. As a new article of manufacture, a wire screen consisting of straight wires running in one direction, of transverse wires having bends or indentations at the points of intersections with the first wires, and of transverse binding-off side wires, substantially as set forth.

2. A wire screen for malt-kilns, floors, and similar purposes, consisting of a series of parallel wires having looped bends, a series of stiffening-wires passing crosswise of the said parallel wires through the loops thereof, and of binding-off wires passing sidewise of the loops below the main wires, substantially as specified.

3. A wire screen for malt-kilns, floors, and similar purposes, consisting of a series of parallel wires, having loop-shaped bends or indentations, of transverse stiffening and binding-off wires passing, respectively, through and sidewise of the loops of the main wires and of short intermediate wires connected to the transverse binding-off wires, for keeping the main wires at a proper distance, substantially as described.

4. The method herein described of making wire screens, consisting in bending a series of parallel wires at certain intervals, next closing the bends, so as to form eyes or loops, then connecting and binding off these wires by straight transverse wires passing through and sidewise of the loops, substantially as and for the purpose set forth.

In testimony whereof I have signed my name to this specification in the presence of two subscribing witnesses.

FERDINAND PRELLER.
